UNITED STATES PATENT OFFICE.

ALBERT L. THURAS, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed October 8, 1923. Serial No. 667,154.

To all whom it may concern:

Be it known that I, ALBERT L. THURAS, a citizen of the United States, residing at East Orange, in the county of Essex, State of New Jersey, have invented certain new and useful Improvements in Electromagnetic Devices, of which the following is a full, clear, concise, and exact description.

This invention relates to electromagnetic devices and more particularly to magnetic structures for telephone receivers and the like.

The object of the invention in general is to provide a vibratory system particularly adapted for telephone apparatus which, as a whole, will have such variable mechanical properties with frequency and displacement that the vibrations of the system will only be limited by its internal mechanical resistances and the radiation resistance of the air, within the range of the frequencies of importance in sound reproduction.

In accordance with the general features of the invention the vibratory system of a magnetic device is provided with elastic means, which at zero frequency, provides a force opposing the magnetic pull on the armature in a manner such as will give a resultant restoring force proportional to the displacement of the armature, and which, under operating conditions makes the vibratory system resonant at substantially all frequencies of importance in sound reproduction.

In its preferred embodiment, the invention provides in an electromagnetic device responsive to sound wave energy vibrations, an armature operable in response to said vibrations, a vibratory member associated with the armature and a plurality of thin sheets of material such as paper or aluminum foil supported in the form of a loose pack against each side of the vibratory member, the sheets in each pack being sufficiently loose to provide air films between adjacent sheets.

When the armature of a telephone receiver of the balanced armature type is in its neutral position in the magnetic field, there is no tendency for it to move toward the pole pieces. However, any displacement from its neutral position will create a pull which increases very rapidly with the displacement and tends to draw the armature to the pole pieces. Heretofore, in re-

ceivers employing balanced armatures, in order to prevent the armature from striking the pole pieces it has been necessary to rely upon either the stiffness of the diaphragm alone or the stiffness of the diaphragm and some auxiliary means such as a spring attached to the armature. These means were necessarily designed to provide an elasticity which was sufficient to overcome the pull on the armature for the maximum displacement, no particular attention being given to the rate at which the elasticity varied for the different positions of the armature. The resultant elasticity, due to the elasticity of the magnetic field and the stiffness of the vibrating system, therefore, varied considerably for the different positions of the armature, and was also unnecessarily large. This resulted in a system in which the amplitudes of vibration were not proportional to the forces applied thereby causing distortion and the large elasticity with its larger mass resulted in an inefficient system for radiating sound energy.

In an ideal magnetic system, the pull on the armature would be inversely proportional to the square of the separation between the armature and the pole pieces. The pull vs. displacement characteristic in this case would be represented by a parabola. This is, however, only roughly true in the commercial types of receivers but the displacement characteristic, due to the magnetic field, is of this general form. It is, therefore, necessary in order that no distortions will result due to the unbalance of the elasticity in the magnetic field to provide a restoring elasticity having the negative characteristic of the elasticity of the magnetic field. If these opposing elasticities were exactly balanced the armature would not return to its neutral position when displaced. It is, therefore, desirable, in order to insure a large and accurate response and prevent freezing of the armature that the mechanical elasticity be slightly greater by a constant amount for all positions of the armature than the magnetic elasticity. This will provide a restoring force proportional to the displacement of the armature.

The above discussion refers only to the static, or non-operating conditions of the vibrating system but it is also necessary to consider the system when operating in response to vibrations at the various frequen-

cies within the sound range. In order to provide a system which is reasonably responsive to all of the frequencies of the impressed vibrations either the dynamic elasticity, or the dynamic mass, or both must be variable. To accomplish this, advantage is taken of the mechanical constants of thin air films, the elasticity of which as is well known varies, within a certain frequency range, substantially as the square of the frequency. Reference is had to E. C. Wente's paper published in the Physical Review, vol. 10, page 39, and I. B. Crandall's paper published in the Physical Review, vol. XI, page 449.

15 Referring to the drawings, Fig. 1 shows a magnetic system suitable for telephone receivers employing the invention in one form; Fig. 2 is an end view of the magnetic system shown in Fig. 1;

20 Fig. 3 shows a modification of the invention;

Fig. 4 is a cross sectional view of the modification shown in Fig. 3;

25 Fig. 5 is a modified form of the invention as shown in Figs. 3 and 4; and

Fig. 6 shows displacement vs. elasticity characteristic curves for structures provided with and without the invention.

30 In the construction shown in Figs. 1 and 2, the magnetic structure comprises an electromagnet 7 to the opposite ends of which magnetic pole pieces 8 and 9 are respectively secured. Each of the pole pieces is provided with a pair of pole extensions 10, 10

35 which are separated to receive a pair of translating coils 11, 11 therebetween and in spaced relation. Extending between the coils and secured to the pole pieces by means of screws 12, 12 are torsion members 13, 13 carrying armature 14 firmly secured to the members by brazing or other suitable means. The pole piece 8 is secured to the upper side of one end of the magnet 7 and the pole piece 9 to the lower side of the other end so as to bring the pole extensions 10, 10 of one pole piece in overlapping relation to those of the other pole piece. The coils 11, 11 are located on the opposite side of the members 13, 13 with the ends 15 and 16 of the armature extending through the openings in the coils, the openings being made of such a size as to permit free movement of the armature during operation of the receiver. The ends 15 and 16 of the armature 14 extend between the opposing pairs of the pole extensions 10, 10 of the pole pieces 8 and 9 and the end 15 carries a rod 17 secured to the vibratory diaphragm 18. Also secured to the end 15 of the armature 14 is a vibratory member 19 parallel to the diaphragm 18. The ends of the vibratory member 19 may be supported between the elastic cushions 20 at each end by means of members 21 and 22 at one end and members 23 and 24 at the other. The cushions

20 are built up of a number of sheets of thin material such as aluminum foil or paper, an equal number of sheets being disposed on each side of the vibratory member 19. The ends of the vibratory member 19 and also the ends of the sheets are perforated to receive the screws 25, 25. The members 21, 22, 23 and 24 are beveled on the surfaces between which the cushions 20 are clamped so as to provide a larger space for the inner ends of the cushions. The sheets at these ends will therefore be only loosely in contact with each other, permitting the presence of air films which provide elasticity for the vibratory system. For vibrations of low frequency, the elasticity is small as the air between the leaves will flow in and out freely. As the frequency increases the air flows out less freely and the stiffness of the air increases. This variation of stiffness with frequency may be of a more complex function due to a greater or lesser number of layers being in motion at different frequencies. In order to compensate for the magnetic pull on the armature due to the steady field, it is only necessary to take into account the elasticity provided by the sheets acting upon each other without considering the elasticity due to the air cushion. However, in order to cause the vibratory system to respond with the greatest amplitude for all of the impressed frequencies, advantage is taken of the elasticity of the air between adjacent leaves of the cushions. It is well known that if a plate is placed in close face to face relation with a vibrating diaphragm, the elasticity of the air will increase substantially as the square of the frequency. For this effect the air film should have a thickness approximately of the order of .0005 of an inch. Inasmuch as the displacement of the vibratory member of loud speaking receivers, electromagnetic recorders and reproducers is considerably larger than this, it is necessary, in order to obtain the same variation in elasticity with respect to the frequency to provide a plurality of spaces each of which may be somewhat smaller but which will total an amount sufficient to permit the vibratory member in such devices to respond properly to the largest amounts of energy which may be used.

100 In the modification shown in Figs. 3 and 4 there is provided a plunger 31 attached to the ends of the armature by means of a rod 30 and operating in a cylindrical chamber 32 attached to a plate 33 which in turn is secured to the magnet 7. Disposed on one side of the plunger 31 are a plurality of thin discs 34 of aluminum foil or paper and on the opposite side of the plunger are a plurality of similar discs 35 perforated at their centers to receive the rod 30. The operation of this modification is substantially the same as that disclosed in Figs. 1 and 2. Fig. 5

discloses a further modification of the structure shown in Figs. 3 and 4. In this modification, heavier discs 36 and 37 of different thicknesses are used between the aluminum discs 34 and 35 respectively which results in a variation of the effective mass as well as the elasticity with frequency.

Referring to the curves shown in Fig. 6, curve A represents the variation in elasticity with displacement due to the magnetic pull on the armature. Curve B represents the variation in the mechanical elasticity with the displacement as obtained by the cushioning means in accordance with the invention. Curve C represents the variation in elasticity with displacement of the armature in the same receiver without the cushioning device of the invention but with an ordinary spring to overcome the force of the magnetic field. Curve D represents the resultant elasticity due to the combined effects of the elasticity of the magnetic field shown by curve A and the mechanical elasticity of the cushioning means shown by curve B. Curve D is obtained by subtracting curve A from curve B. It will be noted from this curve that the elasticity decreases as the displacement of the armature increases. This results in distorting the electrical sound energy which is impressed on the receiver.

A satisfactory cushioning device may be designed by using one hundred circular layers of .6 millpaper with an area of approximately $\frac{1}{2}$ square inch, where the separation is such that the fraction of the total space occupied by the paper is approximately .2. This arrangement has been found to be effective for a receiver of the type disclosed in Patent 1,365,898 of January 18, 1921 to H. C. Egerton. The number of leaves, the dimensions and the space factor will obviously vary for magnetic systems of different construction.

Although the invention has been shown as applied to electromagnetic systems for telephone receivers it may be readily adapted to any electromagnetic device having a vibrating armature.

The invention claimed is:

1. In a magnetic structure, a magnet producing a steady magnetic field, an armature disposed in said field, and cushioning means exerting a force on said armature which varies at zero frequency with displacement of the armature in the same manner as the force due to the magnetic pull on the armature.

2. In a magnetic structure, an armature, a magnet producing a force on said armature varying in a predetermined manner with the displacement of said armature, and cushioning means producing an opposing force on said armature varying with the displacement in the same manner as the magnetic force.

3. In a magnetic structure, a magnet, a

pair of pole pieces carried by said magnet, a vibratory armature in operative relation with said pole pieces, a member secured to said armature and adapted to vibrate therewith, and cushioning means for applying restoring forces through said member to said armature said forces varying with the displacement in accordance with the magnetic force due to said magnet.

4. In a magnetic structure, the combination with a magnet producing a steady magnetic field and pole pieces carried by said magnet, of a vibratory system comprising an armature in operative relation to said pole pieces, a vibratory member attached to said armature, and air cushioning means applied to said member for maintaining the elasticity of said system substantially constant for all positions of the armature in the magnetic field.

5. A magnetic structure comprising a magnet producing a steady magnetic field, pole pieces attached to said magnet, an armature in operative relation to said pole pieces, and means for compensating for the magnetic pull on said armature, said means comprising a plurality of air cushions disposed on each side of said member whereby a constant resultant elasticity is provided for all displacements of the armature.

6. A magnetic structure comprising a magnet producing a steady magnetic field, pole pieces attached to said magnet, an armature in operative relation to said pole pieces, and means for compensating for the magnetic pull on said armature, said means comprising a vibratory member, a plurality of thin sheets of material, and means for supporting said sheets loosely on each side of said vibratory member whereby cushions are formed to provide an elasticity greater by a constant amount for all displacements of the armature than the elasticity due to the magnetic field.

7. In an electromagnetic device having a steady magnetic field, a vibratory system comprising an armature disposed in said field, a plate attached to said armature, a plurality of thin sheets of material, means for supporting said sheets on each side of said plate, and means for supporting said sheets loosely in contact with each other and with said plate whereby cushions are formed providing a restoring force proportional to the displacement of the armature.

8. In apparatus for the transmission of sound wave energy a cushioned vibratory system resonant for all frequencies within the easily audible range and having a constant elasticity for all displacements thereof at zero frequency.

9. In apparatus for the transmission of sound wave energy a vibratory system comprising a plurality of air cushions providing a constant elasticity for all displacements.

ments at zero frequency and an elasticity variable as the square of the frequencies of the vibrations within the range of importance.

- 5 10. A vibratory system for the transmission of sound wave energy, said system having mass and elasticity one of which varies so that its total elastic reactance is substantially equal to its total effective mass reactance at all frequencies within the range of the sounds to be transmitted.
- 10 11. In a vibratory system for the transmission of sound wave energy having a constant effective mass with frequency and a dynamic elasticity which increases substantially as the square of the frequency, said elasticity being so related to the mass that the system as a whole is resonant throughout the sound frequency range.
- 15 12. In a vibratory system for the transmission of sound energy having a plurality of connected masses in which the aggregate dynamic elasticity and the aggregate effective mass change with frequency so as to produce resonance throughout the sound frequency range.
- 20 13. A vibratory system for the transmission of sound wave energy comprising a plurality of connected masses, the aggregate effective mass of which remains constant with frequency; and a structure consisting of a plurality of separate sheets of thin ma-
- 25

terial and intervening thin air films arranged to come into action successively to produce an elasticity which increases substantially as the square of the frequency to make the system as a whole resonant throughout the sound frequency range.

- 30 14. A sound actuated device in which the elasticity increases substantially as the square of the frequency, said elasticity being of such value that at the lowest frequency to be transmitted the elastic reactance is just equal to the aggregate effective mass reactance.

45 15. A device in which the total effective vibrating mass decreases as the frequency increases and the elasticity increases as the frequency increases, the elastic reactance being substantially equal to the mass reactance throughout the voice frequency range.

- 50 16. In a vibratory system for the transmission of sound wave energy, a vibrating system having a total resultant constant elasticity with frequency and having a plurality of elements whose aggregate effective vibrating mass decreases as the square of the frequency, to cause said system to be resonant throughout the sound frequency range.

60 In witness whereof, I hereunto subscribe my name this 27th day of September A. D. 1923.

ALBERT L. THURAS.
